L. WEINSTEIN,
HEEL SECURING PLATE.
APPLICATION FILED SEPT. 10, 1917.

1,280,917.

Patented Oct. 8, 1918.

Inventor:
Leon Weinstein
By Ralph Daenich
his Atty.

UNITED STATES PATENT OFFICE.

LEON WEINSTEIN, OF ST. LOUIS, MISSOURI.

HEEL-SECURING PLATE.

1,280,917.

Specification of Letters Patent.

Patented Oct. 8, 1918.

Application filed September 10, 1917. Serial No. 190,538.

To all whom it may concern:

Be it known that I, LEON WEINSTEIN, a subject of the King of Roumania, residing at the city of St. Louis, State of Missouri, 5 have invented a certain new and useful Improvement in Heel-Securing Plates, of which the following is a specification, reference being had to the accompanying drawing, forming a part thereof.

10 This invention relates generally to boots, shoes, and the like and, more particularly, to a certain new and useful improvement in heel-securing plates, the principal object of my present invention being to provide an 15 inexpensive plate of novel form which may be conveniently employed and applied within the shoe to assist in securing not only the heel upon the shoe, but also the inner and outer soles at the heel of the shoe together.

20 With the above and other objects in view, my invention resides in certain novel features of form, construction, arrangement, and combination of parts, all as will hereinafter be described and afterward pointed 25 out in the claims.

In the accompanying drawing, which illustrates my invention in preferred form, Figure 1 is a sectional view, partly broken away, of a shoe equipped with my 30 new plate;

Fig. 2 is a plan view of the plate; and

Fig. 3 is a sectional view of the plate on the line 3—3 Fig. 2.

Referring to the said drawing, in which 35 like reference characters refer to like parts throughout the several views, A indicates a shoe of usual form and construction, the same including an inner sole 1, lining 2, counter 3, upper 4, and outer sole 5. 6 indicates the heel of the shoe, which is usually 40 at present of wood and held to the outer sole 5 by glue, tacks, or the like.

B indicates a plate preferably of spring metal and normally of concavo-convex form, 45 the plate B having a shape or contour to conform to, and being adapted to fit within, the interior of the shoe A at the heel thereof.

Approximately centrally, plate B is apertured or perforated, as at 7, for a heel-se- 50 curing screw or the like 8. To weaken the plate at the margin of its perforation 7 to countersink the head of screw 8 in the plate when the plate is applied and fixed within the shoe, the plate B is provided with a plu- 55 rality of scores or kerfs as at 9, radiating

from perforation 7, as seen particularly in Fig. 2. Intermediate perforation 7 and the margin of the plate, portions of the plate are struck out and bent obliquely downwardly to provide a series of outwardly disposed yield- 60 ing sole-engaging fingers 10.

In use or operation, a plate B is applied within a shoe A with its fingers 10 loosely engaging at their tips upon the upper face of inner sole 1. A screw 8 is then fitted to 65 the perforation 7, and on the screw 8 being driven through the inner and outer soles of the shoe into securing engagement with heel 6, the metal of the plate at perforation 7, due to the kerfs or scores 9, is bent down- 70 wardly around, and a seat or countersunk for the head of screw 8 thereby provided in the plate B. At the same time, the fingers 10 and also the body of the plate are spread 75 or flattened and the plate thereby caused to bindingly engage the inner sole 1 not only at its fingers 10, but also at and completely around its margin, as illustrated in Fig. 1. The pull of the screw 8 upon the plate is thereby distributed generally over the entire 80 heel portion of the shoe and especially at the margin of the inner sole 1. Thus the plate B and its attaching screw 8 serve not only to rigidly hold the heel 6 upon outer sole 5, but also to preserve the shoe and its shape 85 by assisting in securing the inner and outer soles, with the parts therebetween at the heel of the shoe, together, and at the same time provide a cushion within the shoe for the heel of the wearer. 90

While not here shown, it may be stated that the plate B might be extended to also provide a shank stiffener for the shoe, and that in practice a piece or section of thin leather, felt, or other suitable material is 95 placed within the shoe over the plate B to prevent contact of the foot therewith; other changes in the form, construction, arrangement, and combination of the several parts of my new heel-securing plate might be 100 made and substituted for those herein shown and described without departing from the nature and principle of my invention.

Having thus described my invention, what I claim and desire to secure by Letters Patent is:

1. As a new article of manufacture, a spring-metal shoe-heel securing-plate normally of concavo-convex form, the plate being adapted for placement within the shoe 110

with its concave side toward the insole and when positioned within the shoe yeldingly engaging at its margin upon the insole.

2. As a new article of manufacture, a 5 spring-metal shoe-heel securing-plate, normally of concavo-convex form and apertured approximately centrally for an attaching-screw, the plate being adapted for placement within the shoe with its concave side 10 toward the insole and when positioned within the shoe yeldingly engaging at its margin upon the insole.

3. As a new article of manufacture, a concavo-convex spring metal heel-securing plate 15 for shoes, the plate being provided with a plurality of yielding sole-engaging fingers.

4. As a new article of manufacture, a concavo-convex spring metal heel-securing plate for shoes, the plate having a perforation for 20 an attaching-screw and being provided with a plurality of yielding sole-engaging fingers radially disposed relatively to the perforation.

5. The combination with a shoe and its 25 heel, of a spring metal plate normally of concavo-convex form fitting within the shoe at the heel thereof, the concave side of the plate being presented toward the heel, and an attaching-member passing through the 30 plate into securing engagement with the heel, the plate being caused to bindingly downwardly engage at its margin with the

inner sole of the shoe under the engagement of said member with the heel.

6. The combination with a shoe and its 35 heel, of a spring metal plate normally of concavo-convex form fitting within the shoe at the heel thereof, the concave side of the plate being presented toward the heel, and an attaching-member passing through the 40 plate into securing engagement with the heel, the plate being caused to bindingly downwardly engage at its margin with the inner sole of the shoe under the engagement of said member with the heel, that part of 45 the body of the plate adjacent said margin being spaced from the sole and providing a cushion within the shoe for the heel of the wearer.

7. The combination with a shoe and its 50 heel, of a concavo-convex spring metal plate fitting within the shoe at the heel thereof, the plate being provided with a plurality of sole-engaging fingers, and an attaching member passing through the plate into 55 securing engagement with the heel, the plate being caused to bindingly engage both at its margin and at said fingers with the inner sole of the shoe under the engagement of said member with the heel. 60

In testimony whereof, I have signed my name to this specification.

LEON WEINSTEIN.
